UNITED STATES PATENT OFFICE.

WALTER G. BRIDGE, OF NEWTON, AND WILLIAM A. PERVER, OF WATERTOWN, MASSACHUSETTS, ASSIGNORS TO DR. CHARLES E. PARKHURST, OF SOMERVILLE, MASSACHUSETTS.

MUFFLE FURNACE.

Application filed April 17, 1926. Serial No. 102,659.

This invention relates to electric heating devices, and more particularly to furnaces of the "muffle" type which are designed to bake porcelain or the like. An object of the invention is the provision of a furnace of the above indicated type for use in making artificial dentures, which will be adapted to low cost production, may be easily repaired and will be efficient and convenient in use. A salient feature of the invention is the arrangement of the muffle, whereby the lining and heating elements may be readily renewed, whereby the heat may be uniformly and efficiently supplied to the heating chamber and the material therein, and whereby the muffle may be easily cleaned.

The above and further objects of the invention will become apparent to those skilled in the art upon a reading of the subjoined description and claims in conjunction with the accompanying drawings.

In the drawings,—

Fig. 1 is a top plan view of the improved muffle furnace;

Fig. 2 is a side elevation of the same;

Fig. 3 is a bottom view of the cover;

Fig. 4 is a vertical section on line 4—4 of Fig. 3;

Fig. 5 is a detail view of the muffle;

Fig. 6 is a section on line 6—6 of Fig. 5;

Fig. 7 is a detail sectional view; and

Fig. 8 is a diagrammatic view of the muffle plate assembly.

In its preferred embodiment the muffle furnace illustrated in Figs. 1 and 2 comprises a base 1 provided with supporting legs 2 at its corners. Above the base is located a substantially rectangular bed plate 3 containing a rheostat of standard type, which is actuatable by the handle 5. The furnace proper is located above the bed plate and comprises an outer casing 6 of metal, such as aluminum, with a suitably disposed cover 7, said cover being secured to a pivotally mounted rod 8 provided with an extending handle 9. The rod 8 is secured by pivot 11 to a collar 12 rotatably mounted on upright 10, which comprises a rod extending upwardly from one of the legs 2 of the base member. During use of the device the rod 8 and cover 7 may be moved by means of the handle 9 so that the cover is swung around pivot 11 or collar 12, whereby the cover may be located at any con-

venient point in a substantially inverted position.

The muffle or furnace proper comprises a receptacle 13 of heat insulating material, such as clay, disposed with the supporting ring 18 which has a flange 19 engaged with the upper edge of casing 6. The receptacle 13 has a suitable number of slightly tapered faces each of which abuts a muffle plate 16. Muffle plates 16 comprise a lining for the central chamber 15 and are preferably arranged in hexagonal relation as illustrated more particularly in Fig. 5 and may consist of any suitable refractory material which is also adapted to provide proper electric insulation.

Electric energy is received from an external circuit through the binding posts 23 and the rheostat in the base, and the leads 20 of platinum wire are detachably connected to portions of the radially disposed, insulated supports 23 which are in turn connected to the rheostat. Leads 20 comprise extensions of the looped wires embedded in adjoining muffle plates 16^a and 16^b.

The intermediate muffle plates are each provided with a similar looped wire 21, preferably of platinum or a platinum alloy, a portion 22 of this wire projecting from the vertical edges of each of the plates in juxtaposed relation with similar wires upon adjoining plates, these projecting wire portions being twisted around one another so that a continuous circuit is provided between lead wires 20 through each of the muffle plates and so that the plates are detachably connected to each other. The looped portions of the wire 21 may consist of a series of oppositely disposed open loops which are adapted to serve as heating elements, being located near the inner surface of the plates whereby the maximum amount of heat is supplied to the chamber 15 and whereby a substantial body of heat refractory material is disposed between the heating wire and the heat insulating clay 17.

As illustrated in Fig. 8, the backs of each of the muffle plates are provided with recesses or grooves 25 to accommodate the twisted wire sections 22. Preferably the muffle plates are arranged to have their vertical edges in slightly tapered relation to each other whereby the plates may be quickly removed from the muffle by detachment of

the wire 20 and whereby they may be located in accurate juxtaposition with a wedge-like action when they are assembled in the furnace.

5 The cover 7 is provided with a suitable filler of heat insulating substance such as clay, which is adapted to reflect the heat from the muffle plates. An elongate, substantially cylindrical opening 26 extends 10 through the cover and filler with a hinged cap 27 located at its outer end. This opening with the cooperating cap is adapted to permit the dentist to observe conditions within the fire chamber. Suitable connections 29 may also be provided in the cover for the installation of a pyrometer if the same is desired.

20 At one side of the base member 1 is disposed a suitable stand 30 pivotally mounted on the arm 31 which is itself pivotally mounted on the upright 32 aligned with one leg 2 of base 1. The stand 30 is provided with a tight cover 33 of aluminum or the like.

25 It is to be understood that porcelain dentures or the like may be baked in the muffle furnace described above. A denture is prepared and may be placed upon a clay tray or the like and located within the fire chamber 15. The cover 7 is then located over the chamber, the rheostat being gradually cut out by the operation of handle 5 until the platinum resistance wire 20 is given its maximum temperature. The muffle plates 30 are heated to a high temperature, the temperature within the chamber being gradually less toward its outer wall due to the location of the wire close to the inner surface of the muffle plates and to the thickness 40 of heat insulating material. Uniform disposition of the muffles around the central chamber also ensures the maximum thermal efficiency and consistency of operation of the furnace. If desired the cover 27 45 may be opened so that the dentist may view the condition of the denture during the baking operation. When the baking operation has been completed, the cover 7 may be lifted, the arm 8 being thrown over, and the denture may be removed and located upon the stand 30, being covered with member 33 to permit uniform and gradual cooling.

50 It is now evident that a porcelain furnace has been provided which is comparatively simple and inexpensive, which is provided with muffle plates which may be made interchangeable and may be quickly replaced either in series or individually and that the device has been designed with a careful attention to thermal efficiency, uniformity of working operations, and convenience to the operator.

55 We claim:

60 1. A muffle furnace comprising an outer

layer of heat insulating material and a removable lining comprising a series of separate plates of refractory material provided with heating means adapted to be energized by an electric current, each plate being readily separable from the series and the series being removable from the muffle.

65 2. The subject matter of claim 1 further characterized by the fact that each of the plates are secured to each other by relatively detachable elements comprising electrical connections between heating means in each of the plates.

70 3. The subject matter of claim 1 further characterized by the fact that the plates are secured to each other by projecting pieces of pliable wire bent into engagement with similar pieces upon adjoining units and thus comprising electrical connections for the 80 heating means.

75 4. The subject matter of claim 1 further characterized by the fact that the plates are provided with looped wire portions embedded therein to comprise electric heating means and that projections of the looped wire of each plate are twisted into engagement with similar projections of one or more adjoining plates to form mechanical and electrical connections between the plates.

80 5. The subject matter of claim 1 further characterized by the fact that the plates are provided with looped wire portions embedded therein to comprise electric heating means and that projections of the looped wire of each plate are twisted into engagement with similar projections of adjoining plates to form mechanical and electrical connections between the plates, portions of the plates being recessed to accommodate said 90 twisted wire portions.

95 6. The subject matter of claim 1 further characterized by the fact that the plates are connected to each other by wire forming electrical connections for the heating means and that wire portions which are connected with an external source of energy comprise 100 means detachably holding the series of plates in the furnace.

105 7. The subject matter of claim 1 further characterized by the fact that the plates have their juxtaposed edges tapered and that the adjoining faces of the layer of heat insulating material are correspondingly inclined toward each other, whereby the plates may be located within the furnace in firm 110 contacting relation with each other.

115 8. A muffle furnace comprising a casing having an opening therein through which articles to be heated may be inserted and removed, the surface of said casing adjoining said opening being tapered, a lining in said casing of refractory material comprising a series of abutting plates removably mounted around the inside wall of the casing adjacent said opening, the surfaces of said plates 120

being tapered adjoining the tapered portion of the said casing and the adjoining edges of the said plates being mutually tapered, resistance wire mounted in the interior of the said plates, the plates being slidable through said opening when the said closure is opened.

Signed by me at Boston, Massachusetts, this 16th day of April, 1926.
